UNITED STATES PATENT OFFICE.

FRED C. HAMILTON, OF NEW YORK, N. Y., ASSIGNOR TO "AMERICAN SEAL-LOCK COMPANY," OF SAME PLACE.

IMPROVEMENT IN SEAL-LOCKS.

Specification forming part of Letters Patent No. 122,459, dated January 2, 1872.

Specification of an improved Seal-Lock, invented by FRED C. HAMILTON, of the city, county, and State of New York.

This invention relates to the class of locks which are adapted for use with seals of glass or analogous frangible material. My improved lock consists of a bow or shackle, fitting at its ends in sockets in a cross-bar, and there held by a spring-catch. At one end of the bow it is adapted for the reception of a seal of glass or analogous material, which must be broken before access can be had to the spring-catch to separate the parts.

The details of construction are hereinafter described.

In the drawing, Figure 1 is a perspective view of the lock. Fig. 2 is a longitudinal section of the same.

A represents a rigid cross-bar, formed at its ends with sockets *a a'* to receive the ends *b b'* of the bow B. In the longer and larger end *b* of the bow is formed a seat for the seal S, which, when the parts are locked together, is exposed through an opening in the face of the bar, but cannot escape therethrough in a whole condition. The locking is effected by the spring-catch C, which may preferably consist of a pin pressed forward by a spring, D; but this form of catch is not new in itself, and I do not desire to limit myself to any special shape there-

for. The said pin engages in a hole provided for it in the bow B in such position as to be covered by the seal S. The end B of the bow being elongated, as shown, may be provided with one or more additional openings below the cross-bar to receive lead seals T for additional security.

I apply the invention in locking the doors of a freight-car, for example, which is one use for which the invention is well adapted. The hasp of the door is passed over the staple in customary manner, and the bow B, with the seal S applied, is then passed through the staple and its ends are inserted in the sockets of the bar A, where it is securely held by the spring-catch C. In order to release the parts it will now be needful to break the seal S, after which a pointed instrument is pressed upon the end of the catch C, forcing it back while the bow B is withdrawn.

I claim as my invention—

The seal-lock herein described, consisting of the bow B *b b'*, cross-bar or socket piece A *a a'*, and spring-catch C, all constructed and adapted for use in connection with a seal, S, of glass or analogous material, in the manner and for the purposes specified.

Witnesses: FRED C. HAMILTON.
